UNITED STATES PATENT OFFICE.

BENHARD YOCH, OF BELLEVILLE, ILLINOIS.

MACHINE FOR POINTING CUT NAILS.

SPECIFICATION forming part of Letters Patent No. 465,960, dated December 29, 1891.

Application filed February 12, 1890. Serial No. 340,131. (No model.)

To all whom it may concern:

Be it known that I, BENHARD YOCH, of Belleville, in the county of St. Clair and State of Illinois, have invented a certain new and useful Improvement in Machines for Pointing Cut Nails, of which the following is a full, clear, and exact description, reference being had to the accompanying drawings, forming part of this specification.

10 My invention relates to certain improvements in machines for pointing cut nails; and it consists in features of novelty hereinafter fully described, and pointed out in the claims.

Figure I is a vertical longitudinal section 15 of my machine, taken on the line I I, Fig. V. Figs. II to IV, inclusive, are views of the pointing-dies, Fig. II being a section and Figs. III and IV perspective views, Fig. III showing the dies open and Fig. IV showing them 20 closed. Fig. V is a top or plan view with the cutters and their holder removed. Fig. VI is a perspective view of the nail-discharger. Fig. VII is a section of same, taken on line VII VII, Fig. IX. Fig. VIII is a detail 25 perspective view of same. Fig. IX is an end view of the holding and pointing dies and the nail expeller or discharger. Fig. X is an end view of same, showing a modification of the discharger. Fig. XI is a section taken on line XI XI, Fig. X. Figs. XII and XIII are 30 detail views illustrating the operation of the nail-discharger. Fig. XIV is a vertical transverse section taken on line XIV XIV, Fig. V. Fig. XV is a detail perspective view of the 35 fixed pointing-die and its holder. Fig. XVI is a detail view of the nail before it is pointed. Fig. XVII is a similar view of the nail after it is pointed, but before the fin is removed; and Fig. XVIII is a similar view of the nail 40 after it is pointed and the fin is removed; Fig. XIX is a plan view of one of the pointing-dies; and Fig. XX is a similar view, showing a die not provided with my improved cutting-edge for splitting the fin beyond the point 45 of the nail.

Referring to the drawings, 1 represents the main frame of the machine. 2 represents the movable knife; 3, the fixed knife; 4, the head carrying the movable knife; 5, the lever for 50 moving the knife; 6, the shaft, provided with

a cam 7, for moving the knife-lever; 8, the fixed, and 9 the movable holder for retaining the nail while it is being headed and pointed, and 10 the heading-die. All of these parts are old, so far as my present invention relates, and as they are not a necessary part of the operation of the parts to which my present invention relates, a further description of them is thought to be unnecessary in this application. A description of these parts will 55 be found in my applications now pending filed April 6, 1889, and September 4, 1889, serially numbered, respectively, 306,245 and 322,936.

The movable pointing-die 19 in my present application is supported on the upper end of 60 an arm 20, the head 20^a of the arm being recessed, as shown in Fig. XV, to receive the die, which is held to the arm by means of a plate 21. The inner end of the die fits against a shoulder 22 at the inner end of the recess 65 that receives the die, and thus any backward movement of the die while pointing the nail is prevented, and the plate 21 holds the die from vertical movement, while at the same time it can be quickly taken out to be sharpened and can be easily and quickly replaced. The arm 20 is supported on a shaft or rod 23, fitting in sockets 24 in the frame of the machine. The rod 23 is susceptible of end movement in its bearings, so that the die can thus 70 be adjusted laterally when desired, and, as is often necessary, when a die has been sharpened or when a new die is applied. This adjustment I prefer to effect through means of set-screws 25, which pass through the frame 75 of the machine and are provided with jam-nuts 26, to prevent them from turning accidentally. It will be seen that by loosening on one of the set-screws and tightening on the other the rod 23, and consequently the die-arm 20, may be shifted laterally in either direction, as may be found necessary. The arm 20 is secured to the shaft or rod 23 by means of a bolt 27, which passes through an elongated opening 28 in the shaft or rod, (the shaft 80 or rod at this point being flattened out, as shown in Fig. I.)

29 represents a set-screw passing through the rod or shaft 23 beneath the bolt 27, and which is provided with a jam-nut 30 and a 90 95 100

conical point 31, fitting in a perforation 32 in the arm 20. It is often found necessary to adjust the movable die vertically as well as laterally, and I have provided a means of 5 doing this by the use of the parts just described. It will be seen that by loosening on the bolt 27 and tightening on the set-screw 29 the conical point of the latter will cause the arm 20 to be moved upward, the elongated 10 opening 28 permitting the bolt 27 to be carried upward with the arm. In a like manner, if the die needs to be moved in a downwardly direction, it can be done by loosening on the bolt 27 and turning the conically-pointed 15 screw 29 in an outward direction. I am thus enabled to get both a vertical and a lateral adjustment to the movable die and to get a very fine or accurate adjustment in either direction.

20 It is of course necessary that the mechanism for operating the movable die be such that it will not interfere with the vertical or lateral adjustment just mentioned, and for this purpose I use a link 33, which is pivoted 25 at 34 to the head of the arm 20, and which has a conical recess 35 in its other end, which receives the conical point of a set-screw 36 in a lever 37, which imparts the movement to the die. This connection between the arm 20 30 and the lever 37 permits of the adjustments of the die to which I have referred. The lever 37 is provided with a friction-roller 39 on its free end, which is engaged by a cam 40 on the shaft 6 to force the die forward. The die 35 with the other parts is returned by a spring 41, connected to the bed-plate of the machine at its lower end, and to a rod 42, projecting from the shaft 23 at its upper end.

The nails are liable to stick in the fixed die 40 after being pointed, and for this reason it is necessary or desirable to provide a discharging device, which will relieve them from the fixed die as soon as the dies open. To accomplish this I place a back piece 44 between 45 the fixed holder 8 and the fixed die 45. The parts are shown in their position in Fig. V, and the construction of the discharger is shown in Figs. VI, VII, VIII, and IX. The inner end of the back piece is formed with a 50 recess, producing a shoulder 46, and the plate is grooved, as shown at 47, to receive a plunger 48, behind which is located a spring 49. The spring holds the plunger 48 normally in its outer position, or in the position shown in 55 Fig. VII, and also shown in Fig. XII. As the nail is forced by the movable die and holder up against the fixed die and holder, the plunger 48 is forced from the position shown in Fig. XII to the position shown in Fig. XIII, 60 the nail being brought back against the end 50 of the back piece 44, beneath the shoulder 46. Then as the movable holder and die recede the spring 49 will force the plunger 48 to its outer position and relieve the nail, so 65 that it will drop from the machine.

For the purpose of adjusting the back piece

44, as may be found necessary, I slot its outer end, as shown in Fig. VII, and provide its set-screw 51 with a reduced portion 52, that fits in the slot 53 of the back piece. These 70 parts will be seen by referring to Figs. VI, VII, and VIII. The set-screw 51 passes through the holder that retains the fixed die, the fixed holder, and the back piece 44, and it will be seen that by turning inwardly or 75 outwardly on this set-screw the back piece 44 will be adjusted in and out, as desired.

As a modification of the discharger I have shown two plungers, Figs. X and XI, each plunger having a groove in the back piece 44. 80

In my applications referred to I have shown different kinds or shapes to the faces of the dies for the purpose of producing different shapes of points on the nails. In this application I have shown the cutting-edges 85 arranged in the form of the letter V, (see Fig. XX,) which would produce a point with a fin, as shown in Fig. XVII. It is necessary where this fin adheres to the nail after the die is opened, as it often does, that it be removed, 90 and in one or both of my other applications I have described a device for removing the fin. To assist in the easy removal of the fin I have in this application shown the face of the dies provided with a cutting-edge 60, which 95 splits the fin beyond the point of the nail, as shown by the dotted line in Fig. XVII. This cutting-edge 60 forms a die in the shape of the letter Y, as shown in Figs. III and XIX. By thus splitting the fin beyond the point of 100 the nail it is much easier to remove it from the nail, as stated, and does not add to the cost of the production of the nails..

I claim as my invention—

1. In a machine for pointing cut nails, the 105 combination of a movable die and means for adjusting the die vertically, consisting of a rod to which the die-supporting arm is secured by a bolt fitting in an elongated hole and a conically-pointed screw passing through 110 the rod and fitting in a perforation in the die-supporting arm, substantially as set forth.

2. In a machine for pointing cut nails, the 115 combination of a movable die, means for shifting the die vertically and laterally, consisting of a rod to which the die-supporting arm is secured, set-screws bearing against the ends of the rod, a retaining-bolt by which the arm is secured to said rod, and a conically-pointed set-screw passing through the rod and entering a perforation in the die-supporting arm, 120 substantially as set forth.

3. In a machine for pointing cut nails, the 125 combination of a movable die, means for adjusting the die laterally and vertically, and means for imparting movement to the die, consisting of a link jointed to the die-supporting arm, a lever, a set-screw passing through the lever and having a conical point fitting in a socket in the end of the link, and 130 means for moving the lever, substantially as set forth.

4. In a machine for pointing cut nails, in combination with a fixed and movable die, a nail-discharger consisting of an adjustable back piece 44, provided with a groove and 5 shoulder, and a spring-plunger fitting in said groove, substantially as set forth.
5. In a machine for pointing cut nails, a die having cutting-edges producing a fin, and a splitting-edge extending beyond the point of the cutting-edges, substantially as set forth. 10

BENHARD YOCH.

In presence of—

THOMAS KNIGHT,

E. S. KNIGHT.
